UNITED STATES PATENT OFFICE.

NORRIS ELMORE CLARK, OF PLAINVILLE, CONNECTICUT.

CORNER-BEAD.

1,288,512.

Specification of Letters Patent. Patented Dec. 24, 1918.

Application filed May 21, 1917. Serial No. 169,841.

To all whom it may concern:

Be it known that I, NORRIS ELMORE CLARK, a citizen of the United States of America, residing at Plainville, Conn., have invented 5 a new and useful Corner-Bead, of which the following is a specification.

My invention relates particularly to the so-called clip type of bead. The main object is to provide a construction which can be 10 made cheaply and yet which is strong and rigid, readily erected and affords a secure key for the plaster.

In its preferred form the body of the bead is made of sheet metal folded and shaped 15 so as to have a rounded nose with lateral under-cut shoulders. The sides are preferably brought together immediately back of these shoulders and then spread outwardly and the edges brought toward each other so 20 as to form longitudinal ribs. Between the indented sides and the rib parts of the metal are cut longitudinally and turned inwardly so as to form long, narrow slots and produce under-cut recesses. Through these narrow 25 rows slots attaching clips are inserted and bent to fit the corner to which the bead is to be attached. These clips are preferably provided with longitudinal slots at the points where the clips engage the longitudinal 30 member of the bead so as to provide passages for the cement or plaster and thus insure the better binding together of the parts. The slot is only slightly wider than the thickness of the metal so that when the clip 35 is bent the parts will bind and prevent the accidental displacement of the clip in the process of assembling and erection. Preferably the edges of the bead are bent toward each other at points between the clips 40 so as to afford additional under-cut pockets for the reception of the plaster or mortar.

Figure 1, is a side view of a bead embodying the improvements of my invention showing also in dotted lines the position of a clip 45 bent diagonally to accommodate attachment at the erection point.

Fig. 2, is a rear view of the body showing in dotted lines the possibility of moving the clip longitudinally of the bead to a limited 50 extent.

Fig. 3, is a horizontal section on an enlarged scale showing a fragment of the clip inserted but before bending.

Fig. 4, is a similar view showing the clip 55 bent.

Figs. 5 and 6 are face views of a fragment of a clip showing modifications of details.

Figs. 7 and 8 are edge views of fragments of clips showing other modifications of details.

The nose 10 may be of any desired shape but is illustrated herein as rounded and provided with shoulders 11, 11 which are so shaped as to provide under-cut recesses 12, 12. The sides 13 are preferably bent together to form a central member which is adapted to project outwardly from the angle of the wall. The slots 14, 14 are formed by slitting the metal longitudinally and bending the flanges 15 inwardly so as to form under-cut pockets 16. The walls 17 between the slots are bent outwardly and longitudinally extending ribs 18 are formed extending continuously parallel to the shoulders 11. The rear edges are twisted alternately to the right and left so as to form flanges 19 which extend toward each other. This forms a continuous pocket in the rear of the bead of irregular cross section, the part 21 being deeper than the part 22.

The clips 23 are preferably formed of flat strips of metal somewhat thinner than the width of the slots 14 and somewhat narrower than the length of the slots 14 in the body of the bead. Preferably the clips are 85 provided with central slots 24 so as to permit the plaster or cement to pass through at this point and more closely embed the clip and the body of the bead at the point of connection. This also weakens the clip at this 90 point and thus enables it to be more readily bent together after it is inserted. When the clip is bent as shown in Fig. 4 it will be noted that the central part 25 arches slightly so as to fill in the slot in the body of the 95 bead and prevent shifting of the clip. The slots 14 are preferably formed at frequent intervals and clips may be inserted in any number of these slots at such intervals as desired. The clips may be adjusted up and 100 down as indicated in dotted lines in the lower part of Fig. 2 or they may be twisted as indicated by the dotted lines in the lower part of Fig. 1 so as to bring the nail openings 26 at the point best suited for attachment to the corner.

The clips may also be notched as at 27 in Fig. 5 or at 28 in Fig. 6 so as to insure the bending of the clip at the exact point desired. When the notches are on the outer 110

edges as in Fig. 5 the notches may serve to engage the body of the bead and prevent shifting of the clip therein. The clips may be also provided with a number of corrugations as shown at 29 and 30 in Figs. 7 and 8 so as to engage parts of the body of the bead to prevent relative shifting of the clips. The corners 28' adjacent the notches 28 may be turned up as shown in Fig. 6 to engage 10 the body of the bead and hold the clip if desired.

What I claim:—

1. A corner bead construction having a nose and lateral shoulders with side recesses 15 and narrow longitudinal slots and outwardly flaring portions forming ribs at the edges, the sides of the slots having inturned flanges and the edges of the ribs being bent to the rear so as to form in conjunction with 20 the flanges a longitudinally extending pocket of irregular cross sectional shape.

2. A corner bead construction comprising a body having a nose with side shoulders, indented sides, outwardly flaring walls with 25 narrow longitudinal slots, inturned flanges at the edges of the slots and rearwardly extending edges twisted alternately in opposite directions and forming a longitudinal pocket of irregular cross sections at the 30 rear.

3. A corner bead construction comprising

a body having a nose with side shoulders, indented sides, outwardly flaring walls with narrow longitudinal slots, inturned flanges at the edges of the slots and rearwardly extending edges twisted alternately in opposite directions and forming a longitudinal pocket of irregular cross sections at the rear in combination with attaching clips extending through some of said slots and arched at their central portions to engage 35 the body of the bead along a central line at the crown of the clip and along two lines at opposite sides thereof.

4. A corner bead construction comprising 45 a body having longitudinal shoulders, indented sides and outwardly flaring edge portions with slots between said edge portions and said sides, said slots being arranged in pairs, the slots of each pair being 50 spaced apart laterally to form pockets between the outwardly flaring edge portions in combination with clips arranged in some of said slots, each clip having a central opening with metal on each side thereof whereby 55 the plaster or cement may pass through the central opening and into the slot containing the clip and the pocket in rear of the outwardly flaring edge portions to reinforce the rear of the body and hold the clip in place. 60
